UNITED STATES PATENT OFFICE.

JAMES R. BAKER, OF KENDALLVILLE, INDIANA.

IMPROVEMENT IN LAMPS.

Specification forming part of Letters Patent No. 42,266, dated April 12, 1864.

To all whom it may concern:

Be it known that I, JAMES R. BAKER, of Kendallville, Noble county, and State of Indiana, have invented a new and Improved Lamp-Burner; and I do hereby declare that the following is a full and exact description thereof, reference being had to the accompanying drawings and letters of reference marked thereon, forming a part of my specification, in which—

Figure 1 is a perspective view of my improved lamp; Fig. 2, a like view with the sliding tube elevated; Fig. 3, a sectional view of Fig. 2; Fig. 4, a sectional view of the burner as represented in Fig. 1, but removed from the lamp-reservoir; and Fig. 5, a perspective view of the detachable wick-tube.

In the drawings, the oil-reservoir or lamp-body A has its neck b mounted with a metallic collar, C, in the usual manner and provided with a female screw to receive therein the male screw of the burner, as clearly shown in Figs. 3 and 4. In my case the burner consists, in part, of a short stationary tube, D, fitted to seat itself into the collar C, as indicated in the last-named figures. This tube is perforated, as at e, with an aperture of size sufficient to admit the nozzle of an oil-can, for the purpose of replenishing the lamp with oil, as will be hereinafter described. It is also provided with a series of small perforations, f, to admit air to the lamp when burning, and one of which, being somewhat enlarged, serves to receive and support one end, g, of the thumb-screw h of the wick-tube I, while the opposite end is supported in the open slot or "gain" k, formed in the top of the tube D.

The wick-tube I, clearly shown in Fig. 5, is provided with a semicircular foot-piece, l, to correspond with the inner portion of the collar D, and serves to retain the wick-tube in a vertical position in conjunction with the projecting detent l', attached to the sliding half-tube N, when the latter is in the position represented in Figs. 1 and 4. The office performed by the parts l l' is also assisted by the tubular form of the sliding half-tube N at the point m, since such point or part surrounds the wick-tube when the burner is made to assume the position shown in Figs. 1 and 4.

The part N, as clearly shown in Figs. 3 and 4, is constructed in the form of a half-tube, with the exception of its extreme upper portion, m,

which, as beforestated, is tubular, and is perforated, as at e', in the same manner and for the same reason that the aperture e is made in the collar D. This half-tube or sliding portion N is made of such length that when elevated as shown in Figs. 2 and 3, the tubular portion m will rise above the top of the wick-tube I, and, whether elevated or depressed, is retained in its proper relation to and within the collar D by "stops" p, projecting from the interior of the collar D, and against which the edges p' of the half-tube N slide when said tube is in the act of being elevated or depressed, and against which stops catches p² abut when the half-tube is elevated to the position shown in Fig. 3, and so prevent said part N from being entirely withdrawn from the collar D.

By reference to Fig. 1 it will be seen that when the lamp is closed there is no access to the oil-reservoir A through the opening e, but when the burner is elevated, as shown in Fig. 3, the openings e and e' exactly register, and that in this position the body of the lamp may be filled with oil. It will also be seen that in the act of replenishing the lamp the wick-flame r will be far removed from the openings e e', and on the opposite side of the sliding half-tube N said part N, thus in the act of filling the lamp with oil, serving as a shield against the ignition of the oil and the consequent explosion of the lamp in case volatile oils are used. It will also be seen by reference to Figs. 2 and 3 that when the burner is in an elevated position the wick-tube I may be turned out into a convenient position for trimming the wick, and this can be done while the wick is ignited without danger of explosion, as the flame will be far removed from the openings e e', and also protected from the evaporation of the volatile oil by the interposing portion of the part N. It will further be seen that the entire wick-tube I, as shown in Fig. 5, may be removed from the body of the lamp for the purpose of supplying a new wick, when the burner is in the elevated condition represented in Figs. 2 and 3, to effect which it is only necessary for the operator to lay hold of the thumb-screw h, raise the rod r out of the slot k and withdraw the end g of the rod r out of the enlarged perforation f, situated opposite to the slot k in the collar D. It is only necessary further to state that the sliding portion N above its tubular part m is

made to expand into the usual circular perforated base t and gallery t' , made to receive and hold in place the lamp-cone t^2 and lamp-chimney t^3 by means of the screw t^4 as ordinarily practiced, and lastly, that the air-holes f of the collar D and the air-holes f' of the part N exactly register, to admit air to the flame when the lamp is made to assume the position shown in Fig. 1.

Having thus described my invention, what I claim as new, and desire to secure by Letters Patent of the United States, is—

1. So combining a wick-tube with a lamp-burner that it may be turned outward by its thumb-lever h r g for the purpose of trimming the wick, or be removed therefrom for the purpose of supplying a new wick, substantially as set forth.

2. So applying a wick-tube to a lamp-burner that the flame of the lamp when the wick-tube is turned outward for the purpose of trimming the wick will be in a direction oppo-

site to the oil-supply openings of the lamp, and with an interposing portion of the lamp-burner between the flame and the oil-supply openings, substantially as described.

3. The foot-piece l , in combination with the wick-tube I, for the purpose set forth.

4. The detent l' , in combination with the wick-tube I and foot-piece l , for the purpose set forth.

5. The tubular portion m of the sliding half-tube N, in combination with the wick-tube I, substantially as and for the purpose set forth.

6. In combination with the collar D, having opening e therein, the sliding half-tube N, with opening e' therein, said parts being arranged and operating substantially in the manner and for the purpose set forth.

JAMES R. BAKER.
